UNITED STATES PATENT OFFICE

HARRY D. WEED, OF SYRACUSE, NEW YORK.

GAS-ENGINE.

SPECIFICATION forming part of Letters Patent No. 659,944, dated October 16, 1900.

Application filed March 24, 1900. Serial No. 10,108. (No model.)

To all whom it may concern:

Be it known that I, HARRY D. WEED, a citizen of the United States, residing at Syracuse, in the county of Onondaga and State of New York, have invented certain new and useful Improvements in Gas-Engines, of which the following is a specification, reference being had to the drawings accompanying and forming a part of the same.

The invention subject of my present application is an improvement in gas-engines, more particularly of the class known as "two-cycle explosive-engines," and has for its main objects to simplify and improve the construction of such engines, to increase their efficiency, and to provide for a better regulation of the same, especially with a view to rendering them more available in small sizes for use in the propulsion of vehicles and other analogous purposes.

The specific features of the invention are largely matters of constructive detail; but a prominent feature to which I attribute much of the practical success of the engine consists in a means for regulating the force of the explosion in proportion to the amount of work which the engine is called upon to perform and which, stated in general terms, is as follows: In conjunction with a working cylinder and a gas-chamber and a piston common to both I employ means for introducing into the working cylinder from the gas-chamber a full charge of mixed gas and air at or near the end of forward movement of each stroke, which displaces the gaseous products of combustion within the cylinder and is then prior to ignition compressed by the return of the piston. Under conditions of full load, when the maximum expansive effect of each explosion is required, the whole charge of mixed air and gas is retained and exploded within the cylinder; but should the load be lessened the maximum explosive effect would be in excess of the requirements of the work to be done. To compensate for this, I provide means, preferably automatic, by which a portion of the unexploded charge corresponding in amount to the decrease in load is withdrawn from the working cylinder and returned through a suitable by-pass to the opposite side of the same, so that the actual

charge which remains to be exploded is proportioned in amount to the work which the engine is called on to perform.

In the accompanying drawings, which illustrate the improvement in the best form of which I am now aware, Figure 1 is a central vertical section of an engine embodying my invention. Fig. 2 is a view in side elevation of an automatic governor. Fig. 3 is a similar view of the same from the opposite side. Fig. 4 is a view, partly in section, of the igniting device.

The engine is provided with an extended cylinder, comprising the working or explosion chamber P and the gas-chamber N, through the sides of which latter the main shaft M passes and within which is the crank, connected to the piston Y by the rod A. At the lower end of the cylinder a puppet or other valve F is placed to admit a mixture of air and gas from pipe E into the gas-chamber N.

An igniter of any proper construction is located in the upper end of the working cylinder P; but I prefer to employ for this purpose a specially-designed device which is illustrated in detail in Fig. 4.

O is an eccentric on the main shaft, which gives motion to a strap having a tubular socket-like extension G. In the latter is a rod U, retained within the socket against the force of a spiral spring G' and prevented from rotating by a pin g, passing through the rod and two vertical slots in the socket. The rod 55 works through a guide L, which is secured to the frame of the engine. From the arrangement described it is evident that the upper end of rod U reciprocates vertically and also oscillates from side to side. This motion is 60 taken advantage of to cause the end of the rod to engage with and raise a spring-actuated arm V, fixed to a rock-shaft 6, that extends into the cylinder P, where it carries a metallic arm 2. When the rod U engages and raises 65 the arm V, the arm 2 is turned into engagement with an insulated electric terminal 3 and caused to make good electrical contact therewith, but the upward movement of the rod U being succeeded by a lateral movement 70 of its end it disengages the arm V, which being retracted by its spring effects a sepa-

tion of the contacts 2 and 3, with the formation of a spark that ignites the charge in the cylinder.

Such further details of construction as have not been described will be understood from a statement of the operation of the engine.

It being assumed that at each upward or return stroke of the piston an explosive mixture is drawn into the chamber N through 10 the valve F and that such charge is compressed by the downstroke of the piston, we may consider the action of the latter from the point in its course at which it has opened the port C, communicating with chamber N, 15 and admitted a charge of the mixture to the cylinder P. During the upstroke of the piston the gas thus admitted is compressed and near the end of the stroke ignited. The force of the explosion impels the piston forward until port D is opened and permits the burned gases to escape. The opening of the exhaust-port D is in advance of the opening of the inlet-port C, so that the pressure in chamber P is relieved before a fresh charge 20 is admitted. A baffle-plate J is placed on the piston Y to deflect the entering charge of gas, imparting to it an upward direction, thereby forcing out through port D the remaining burned gases.

25 The passage B, which conducts to the port C the mixture of gas and air, is extended to form a by-pass from the chamber N to the upper end of the chamber P, and in this by-pass is located a valve H of any suitable kind 30 to control the passage. When the explosion of the full charge in the cylinder P develops more power than is needed, the valve H is opened during the upward stroke of the piston, thereby permitting a portion of the 35 charge to escape from the cylinder P and return to the chamber N. This valve may be operated or controlled in any suitable manner; but I prefer to use for the purpose an automatic governor, such as is shown in Figs. 40 45 2 and 3. In said figures, S shows an eccentric, the throw of which is controlled by the position of the pivoted weighted arms W W. The eccentric is provided with an elongated opening O' and has a projecting arm S', which 50 is rigidly fastened to the stud W', upon which one of the weighted arms W is mounted. The studs W' W' carry gears K', which engage with a gear K, mounted on shaft M, and operate to move weights W' W in unison. The 55 governor-springs T' are attached to yoke-pieces T T, which are connected to the weighted arms W by means of studs X, and a series of holes E' are provided in the weighted arms, by means of which the points of connection 60 between the arms and the yoke-pieces made by the studs X may be varied to regulate the speed of the engine. The automatic regulator is adjusted in the manner described according to the speed desired and operates 65 to open the valve H to a greater or less extent during the upward movement of the piston Y and to permit a portion of the charge

to pass back into the chamber N. The extent to which valve H is thus opened will obviously depend upon the speed of the engine 70 and the position of the weighted arms W consequent thereon.

By admitting at each stroke a full charge I am enabled to expel all of the gaseous products of combustion, thus insuring an explosion at each stroke, regardless of the amount 75 of the inflammable mixture which the cylinder contains at the instant when the spark passes; and by the employment in this connection of a working cylinder, a gas-chamber, 80 and a piston common to both, in combination with means by which a portion of this full charge before explosion, according to 85 variations in the load, is withdrawn from the working cylinder on the one side of the piston and returned to the gas-chamber on the other side of the piston, I am enabled to secure 90 in the engine a high degree of efficiency, coupled with simplicity of construction and economy in the space occupied by the structure.

As it may happen when the engine is running light that the explosive charge is not sufficient to maintain a pressure in the cylinder P to the end of the forward stroke of 95 the piston, I provide a valve I of any suitable kind that opens readily inward and permits air to flow into the cylinder upon a predetermined reduction of pressure therein, and thus prevent any tendency to a vacuum back of the piston. It will be understood from the above that when the engine is running on anything less than maximum load the amount of gas within the working cylinder at the time the explosion takes place is reduced in proportion to the reduction of the load of the engine, so that when the piston arrives in position to uncover the exhaust-port D the gases within the working cylinder will be under less compression than when the engine is 100 working at the maximum load, so that the noise made by the exhaust is correspondingly lessened.

I do not restrict myself to the special structural details nor to the precise location and arrangement of the ports and passages hereinbefore described and illustrated, inasmuch as the same can be varied to some extent without departure from the invention; but,

Having now described my invention, what I claim is—

1. In a gas engine the combination with a working cylinder, a gas-chamber communicating with said cylinder and a piston common to both said cylinder and said chamber, of means for admitting to the working cylinder full charges of explosive gas from the gas-chamber and means whereby a portion of the admitted charge of gas proportionate to the amount of work the engine is called upon to perform is withdrawn from the working cylinder prior to ignition, substantially as and for the purposes hereinbefore set forth.

2. In a gas-engine, the combination with

- the working cylinder, the gas-chamber and the piston, the working cylinder being connected with the gas-chamber through ports controlled by the piston, and also through a 5 by-pass from its upper or rear end, of a valve in said by-pass for permitting a portion of an admitted charge, prior to ignition, to pass from the working cylinder back to the gas-chamber, as set forth.
- 10 3. In a gas-engine the combination with a working cylinder, a gas-chamber, and a piston which in its forward movement compresses the explosive mixture in the gas-chamber, and in its return movement, the 15 charge admitted to the working cylinder, the latter and the gas-chamber being connected through ports controlled by the piston, and also by a by-pass, of a valve in said by-pass, and means for controlling the action of the 20 same for permitting a portion of the charge admitted to the working cylinder to pass back
- to the gas-chamber, as and for the purpose set forth.
4. In a gas-engine the combination with an extended cylinder one end of which constitutes the working cylinder or combustion-chamber, and the other a chamber for the explosive mixture, the two being connected by a direct passage and by a by-pass, of a piston working in the cylinder, and controlling in 25 its movement the exhaust-port and also the inlet-port for admitting an explosive charge from the gas-chamber to the working cylinder, a valve in the by-pass and an automatic governor for operating the same, to permit 30 portions of the compressed charges in the working cylinder, before ignition, to pass back to the gas-chamber, as set forth.

HARRY D. WEED.
